UNITED STATES PATENT OFFICE.

CLEMENT A. DUNBAR, OF DETROIT, MICHIGAN, ASSIGNOR TO THE DUNBAR MANUFACTURING COMPANY, OF SAME PLACE.

NON-REFILLABLE BOTTLE.

SPECIFICATION forming part of Letters Patent No. 595,612, dated December 14, 1897.

Application filed November 14, 1896. Serial No. 612,088. (No model.)

To all whom it may concern:

Be it known that I, CLEMENT A. DUNBAR, a citizen of the United States, residing at Detroit, in the county of Wayne and State of Michigan, have invented certain new and useful Improvements in Non-Refillable Bottles, of which the following is a specification, reference being had therein to the accompanying drawings.

10 The invention consists in the peculiar construction, arrangement, and combination of parts, as more fully hereinafter described and claimed.

In the drawings, Figure 1 is a vertical central section through a bottle to which my device is applied. Fig. 2 is a perspective view of the detached parts composing the device; and Fig. 3 is a section similar to Fig. 1, showing the bottle in position to be emptied of its 20 contents.

A is a bottle. B is the neck thereof, which is formed with a contracted portion C near its lower end and preferably with an annular recess D near its mouth.

25 E is a tubular casing having a contracted lower extension F, united to the main portion of the casing by the annular shoulder G.

H is a series of perforations in the sides of the tube E above the shoulder G.

30 H' are apertures in the side of the tube F.

I is a packing-ring, of cork or similar material, surrounding the tube F below the shoulder G and adapted, when the casing is placed in the neck of the bottle, to fit tightly into the contracted portion C.

35 J is a valve comprising the head a, the contracted tubular downward extension b, adapted to fit within the tube F, and the annular shoulder c on the under side of the head, adapted to seat upon the shoulder G. The

40 head a is provided with a float which may be formed either by attaching to it a piece of cork or other light substance or, as shown in drawings, by making within the head an air-chamber e.

45 f is a series of perforations in the walls of the tube b; and d is an imperforate portion between the said perforations f and the shoulder c.

50 K is a thread or flexible connection attached

to the lower side of the head a and extending down through the tube b.

L is a weight (preferably a glass sphere) which is attached to the lower end of the connection K.

55 M is a partition or baffle-plate extending across the casing E. This I preferably form as the bottom of a cup-shaped casing N, fitting into the upper end of the casing E against a bead g and forming an upward extension 60 of said casing. Near its upper end the casing N is provided with a series of perforations h.

In practice after the bottle is filled the casing containing the valve is placed in the neck of the bottle, the packing-ring I fitting into 65 the contracted portion C. The casing is then secured by expanding the upper end of the casing N, so as to fit within the annular recess D, as shown in Fig. 1. To pour out the liquid from the bottle, it is only necessary to 70 incline it to a sufficient angle for the weight L to run down the tapering shoulder O of the bottle, which will relieve the tension on the connection K and allow the valve J to open outwardly. The end of the tube F forms a 75 seat which will catch the weight and prevent it from falling into the neck of the bottle, and the liquid will pass through the aperture H' into said tube and into the tube b, passing through the perforations f and H into the annular space R, surrounding the casing E, and thence through the perforations h out to the mouth of the bottle, as shown in Fig. 3. That the bottle, when once emptied, cannot be refilled will be readily understood, as it will be 80 seen that the only way in which the valve J can be opened is to invert or downwardly incline the bottle, and if in this position it were immersed in the liquid the float would carry the valve to its seat.

90 In order to make a bottle which really cannot be refilled, it must be so constructed that the refilling cannot be accomplished by any of the manipulations or tests usually applied to refill such bottle. It is found that any 95 valve, whether counterweighted or spring-backed, unless it be a piston-valve which is to be slipped some distance longitudinally to disclose the ports it controls, is not safe for this purpose, for the bottle can be refilled by 100

submerging it and then quickly reciprocating it in a horizontal position, or slightly inclined from the horizontal. A piston-valve will not fulfil the conditions required for a 5 non-refillable bottle unless it is associated with two other elements. One is a float or buoyant element which will close the valve by its buoyancy in case the bottle is submerged in an inverted position. The other is 10 a counteracting weight which will draw it to its seat positively in any position except it is substantially in an inverted position. I have found, therefore, what I deem to be the essentials of a non-refillable bottle, so far as 15 my invention goes, are to combine in a filling aperture or neck of the bottle a piston-valve adapted to be moved longitudinally to close or disclose the ports it controls, and having a buoyant element which will close the valve 20 and hold it closed in any inverted position of the bottle when submerged in liquid, and a counteracting weight sufficient to overcome the buoyancy of the valve which is applied in the upright position of the valve or positions approaching the upright. 25

What I claim as my invention is—

1. In a non-refillable bottle, the combination with a bottle-neck, of a valve mechanism for permitting the outflow and prohibiting 30 the inlet of liquid, and comprising a ported casing, a buoyant piston-valve for governing the ports of the casing, and provisions whereby the valve may have an extended recipro-

cating movement while acting to close the ports, and a counteracting weight. 35

2. In a non-refillable bottle a buoyant elongated piston-valve, an elongated seat over which the valve has to move to be opened and a counteracting weight suspended by a flexible cord within the bottle. 40

3. In a non-refillable bottle, the combination with a cylindrical casing within the neck of the bottle provided with an annular valve-seat at its inner end, of a buoyant piston-valve slidingly secured in said cylindrical casing and having outlet-ports adapted to be disclosed by the outward movement of said piston, a head on said piston adapted to seat on said annular seat and a weight within the bottle suspended from said valve for holding it 45 in its closed position. 50

4. In a non-refillable bottle, the combination with a cylindrical casing within the neck of the bottle, of a piston-valve slidingly secured in said cylindrical casing and having 55 outlet-ports adapted to be disclosed by the outward movement of the valve, a float secured to said valve and a weight within the bottle suspended from said valve for the purpose described. 60

In testimony whereof I affix my signature in presence of two witnesses.

CLEMENT A. DUNBAR.
